UNITED STATES PATENT OFFICE.

JOHN M. KANE, OF PARKERSBURG, WEST VIRGINIA.

DERRICK.

1,031,123.

Specification of Letters Patent.

Patented July 2, 1912.

Application filed April 5, 1912. Serial No. 688,637.

To all whom it may concern:

Be it known that I, JOHN M. KANE, a citizen of the United States, residing at Parkersburg, in the county of Wood and State of West Virginia, have invented certain new and useful Improvements in Derricks, of which the following is a specification.

The present invention relates to a metallic derrick and has particular reference to a structure of the above mentioned character, which is strong, and formed of few and simple parts, which may be securely held together and readily separated.

An important object of the invention is to provide a metallic derrick having corner constructions, the parts of which are held together by the minimum number of bolts in a simple manner, without the aid of securing plates or other devices.

Other objects and advantages of the invention will be apparent during the course of the following description.

In the accompanying drawings forming a part of this specification and in which like numerals are employed to designate like parts throughout the same, Figure 1 is a perspective view of one corner of the derrick, and, Fig. 2 is a horizontal sectional view taken above the horizontal T-irons.

In constructing my improved metallic derrick, I provide corner uprights 1, arranged in end to end relation and slightly spaced. These corner uprights are formed of metal, such as iron or the like, and are substantially V-shaped in horizontal cross-section. The uprights 1 are disposed so that their faces which are disposed at an obtuse angle are arranged outermost, as shown.

The numeral 2 designates horizontal T-irons, as shown. The T-irons 2 comprise flat body portions 3, upon the outer face of which are formed flanges 4, as shown. The body portions 3 may preferably have their adjacent ends beveled, as shown at 5, and the horizontal flanges may also have their adjacent ends beveled, as shown at 6, to form a close fitting construction. The angle-irons or uprights 1 are disposed above and below the horizontal flanges 4 and upon the outer faces of the body portions 3 of the T-irons.

The numeral 7 designates diagonal strips or braces which have their free ends bevelled, as shown at 8. The diagonal strips 7 are disposed upon the outer faces of the angle-irons or uprights 1. The body portions 3, uprights 1, and diagonal strips 7 are provided with openings for receiving bolts 9, which securely hold these parts together. It is thus seen that all of the parts of the derrick at each corner are held together by only four bolts, forming a strong simple construction.

It is to be understood that the form of my invention herewith shown and described is to be taken as a preferred example of the same, and that certain changes in the shape, size, and arrangement of parts, may be resorted to without departing from the spirit of the invention or the scope of the subjoined claims.

Having thus described my invention, I claim:

1. In a derrick or the like, horizontal T-irons, uprights formed substantially V-shaped in horizontal cross section and disposed above and below the horizontal flanges of the T-irons in engagement therewith, and bolts passing through the uprights and the body portions of the T-irons.

2. In a derrick construction, horizontal T-irons formed of upstanding body portions carrying horizontal flanges, corner uprights formed substantially V-shaped in horizontal cross-section and disposed upon the outer faces of the body portions of the T-irons adjacent the meeting ends thereof and above and below the horizontal flanges, diagonal strips disposed near the corner uprights, and bolts passing through said diagonal strips, corner uprights, and body portions of the T-irons.

3. In a derrick construction, horizontal elements comprising upstanding body portions provided with outwardly extending horizontal flanges, said elements being arranged at approximately a right angle and having their free ends disposed adjacent each other, corner uprights formed substantially V-shaped in horizontal cross-section and having their faces which are disposed at an obtuse angle arranged outermost, said corner uprights being placed in engagement with the outer faces of the upstanding body portions of the horizontal elements above and below the horizontal flanges and in engagement therewith, diagonal strips placed

in engagement with the outer faces of the corner uprights above and below the horizontal flanges and having the end portions thereof which engage the horizontal flanges 5 beveled, and bolts passing through the ends of the diagonal strips, the corner uprights and the upstanding body portions of the horizontal elements above and below the

horizontal flanges thereof, substantially as described.

10

In testimony whereof I affix my signature in presence of two witnesses.

JOHN M. KANE.
